HANDLE FOR A FILING CABINET

Anton J. Kuhn, Philadelphia, Pa., assignor to
Peerless Steel Equipment Company, Philadel-
phia, Pa., a corporation of Pennsylvania

Original application November 15, 1951, Serial
No. 17,417. Divided and this application Oc-
tober 21, 1952, Serial No. 21,917

Term of patent 14 years

(Cl. D10—8)

To all whom it may concern:

Be it known that I, Anton J. Kuhn, a citizen of the United States of America, residing at Philadelphia, in the county of Philadelphia and State of Pennsylvania, have invented a new, original, and ornamental Design for a Handle for a Filing Cabinet, of which the following is a specification, reference being had to the accompanying drawings, forming a part hereof. The present application is a division of a prior application filed by me on November 15, 1951, under Serial No. D. 17,417.

Fig. 1 is a top plan view of a handle for a filing cabinet showing my new design.

Fig. 2 is an elevational view thereof;

Fig. 3 is a fragmentary bottom plan view taken as indicated by the arrows III—III in Fig. 2;

Fig. 4 is a sectional view taken on line IV—IV of Fig. 2.

Fig. 5 is a perspective view.

I claim:

The ornamental design for a handle for a filing cabinet, as shown.

ANTON J. KUHN.
